CLAIM

The ornamental design for an umbrella base, as shown and described.

DESCRIPTION

FIG. 1 is a top perspective view of an umbrella base showing our new design;

FIG. 2 is a left side elevational view thereof, the right side and front and rear being a mirror image; and,

FIG. 3 is a top plan view thereof.

The broken lines shown in FIGS. 1-3 are for illustrative purposes only, and form no part of our claimed design. The bottom of the umbrella base is unornamented and forms no part of our design.
